(57) **CLAIM**

We claim the ornamental design for a display panel of a programmed computer system with a graphical user interface, as shown and described.

DESCRIPTION

FIG. 1 is a front view of a first embodiment of a display panel of a programmed computer system with a graphical user interface.

FIG. 2 is a front view of the first embodiment of the display panel, on an enlarged scale, for ease of illustration.

FIG. 3 is a front view of a second embodiment of a display panel of a programmed computer system with a graphical user interface.

FIG. 4 is a front view of the second embodiment of the display panel, on an enlarged scale, for ease of illustration.

FIG. 5 is a front view of a third embodiment of a display panel of a programmed computer system with a graphical user interface.

FIG. 6 is a front view of the third embodiment of the display panel, on an enlarged scale, for ease of illustration.

FIG. 7 is a front view of a fourth embodiment of a display panel of a programmed computer system with a graphical user interface; and,

FIG. 8 is a front view of the fourth embodiment of the display panel, on an enlarged scale, for ease of illustration.

The broken lines showing of the display panels are included for the purpose of illustrating environmental structure; the broken lines form no part of the claimed design.
